REFRIGERATOR AND TEMPERATURE REGULATION THEREIN

Jacob H. Hoffberger, Baltimore, Md., assignor to
Merchants Terminal Corporation, Baltimore,
Md., a corporation of Maryland

Application June 26, 1933, Serial No. 677,731

5 Claims. (Cl. 62—46)

This invention is directed to temperature regulation and control in refrigerators, particularly those employing ice, either dry or water ice as the source of refrigeration, and is particularly concerned with structures in which temperature regulation and control is maintained substantially uniform and with minimum consumption of ice.

In refrigerators of the prior art in which ice is used for cooling purposes, circulation of air through the ice compartment has usually been employed, and the structure is designed to permit such circulation for two purposes, such as cooling or refrigerating the air before it passes back into the food compartment, and second because some washing effect is obtained by such contact of the circulating air with the ice.

These prior art types of refrigerators in which air circulates into the ice compartments are relatively inefficient, requiring relatively large quantities of ice in order to maintain temperatures for refrigerating purposes, and further because the temperature varies materially with the quantity of ice in the ice compartment.

In more recent years applicant has developed refrigerator structures in which more uniform temperature control in ice refrigerators is obtained through the utilization of metallic floor plates for supporting ice in such ice compartments, which floor plates are desirably provided with radiating fins enabling more ready control and much more uniform regulation of the temperature in such refrigerators.

The present invention is particularly concerned with the use of such regulators in ice refrigerators. Among the objects of the present invention are refrigerator structures in which the ice compartment is sealed against the entry of air from the food compartment by means of such temperature regulators, the temperature regulators preferably, however, being removable for sanitary purposes, such as cleaning, etc.

Other and further objects and advantages of the present invention include structures in which the temperature regulators are made in two parts associated together to constitute the heat exchange medium between the circulating air of the food compartment and the refrigerant of the ice compartment, which two-part temperature regulator by varying the relation of one part to the other, and by making the two parts of different heat conductivity, permits of more accurate temperature control in the refrigerator.

Still further objects and advantages will appear from the more detailed description set forth

below, it being understood, however, that this more detailed description is given by way of illustration and explanation only, and not by way of limitation, since various changes may be made therein, by those skilled in the art without departing from the scope and spirit of the present invention.

In connection with that more detailed description, there is shown in the accompanying drawing, in

Figure 1, a vertical sectional view through an ice refrigerator constructed in accordance with the present invention; in

Figure 2, a fragmentary transverse sectional view of the refrigerator of Figure 1; in

Figure 3, a plan view of the temperature regulator shown in the refrigerator of Figures 1 and 2; in

Figure 4, a fragmentary perspective view of a portion of the floor plate of Figure 3; and in

Figure 5 an inverted fragmentary perspective view of the separable portion of the floor plate carrying heat radiating fins.

As illustrated in the drawing, the invention will be described utilizing the ordinary type of home refrigerator having an upper ice compartment that extends across the entire upper portion of the refrigerator, but it will be understood that in describing the invention in connection with such type of refrigerator no limitation is intended as to the same principles and structures may be employed with any other type of refrigerator employing ice or similar refrigerant, whether such ice be dry or water ice. In this type of refrigerator, the refrigerator itself is generally denoted by R, and the usual doors by D. In such structures the ice compartment is indicated at 1 and the food compartment at 2.

Further in the form of invention illustrated in the drawing, the temperature regulator is employed to seal the ice compartment against any substantial entry of air from the food compartment, although these temperature regulators constructed in accordance with the present invention may also be used in those types of refrigerators where air is permitted to enter from the food compartment into the ice compartment; in which event the temperature regulator would be supported in any convenient manner on the walls or regular floor of the ice compartment while permitting air to circulate into contact with such temperature regulator and around its edges.

In the preferred form of invention, however, as set forth in the drawing, the temperature regulator seals the ice compartment against any

substantial entry of air thereinto. Thus the floor plate 3 is made of a size corresponding with the cross section of the ice compartment in which it is to be used, so that when placed in position in the ice compartment, and preferably to constitute the floor thereof, the plate seals the ice compartment substantially against the entry of air from the food compartment. For this purpose the plate 3 may simply rest on supporting shoulders 4, 5, 6 and 7 attached to the interior walls of the refrigerator, or any other equivalent or similar supporting means may be employed. This construction supplies a floor plate which is readily removable at will from the ice compartment for purposes of sanitation in order to clean such plate, after which it may be readily replaced in position. If desired, the plate 3 might be held in position by readily removable screws or bolts, but these have been found to be unnecessary.

In the preferred form of this invention, the floor plate 3 is constituted by a flat horizontal portion 8 constituting the front portion of the floor plate to which is attached a rectangular frame portion 9 that provides an opening 10 for purposes hereinafter described. The opening 10 may be provided by merely cutting away a portion of the flat portion 8 of the floor plate leaving surrounding ledges 11 and 12 defining the said opening. Desirably an upstanding lip or ledge 13 is formed along each side portion of the floor plate, while an upstanding lip or ledge 14 is provided along the rearward edge thereof. These upstanding lips 13 and 14 serve to form a strengthening and reinforcing structure for the floor plate 3. A metallic insert, slightly larger than the opening 10 of the floor plate 3, is provided to close the opening 10. This metallic insert plate 15 (see Figure 5) is made of a size sufficiently great so that the extending edges of the plate 15 rest on the ledges 11, 12 of the floor plate 3 defining the opening 10. As a result when the metallic plate 15 is inserted in position, the opening 10 of the floor plate 3 is completely closed. The metallic insert plate 15 is preferably made of a metal dissimilar from the floor plate 3, and the metal of the plate 15 is desirably made of greater heat conductivity than the metal of the floor plate 3 for purposes hereinafter set forth. Desirably all parts are of metal insofar as the floor plate 3 and metallic plate 15 are concerned, but in any event, the metallic insert plate 15 is made of metal so that it will have a relatively high conductivity, and when both the floor plate 3 and metal plate 15 are of metal, then the insert plate 15 is preferably made of metal having a higher heat conductivity than that of the floor plate 3. To increase the heat conductivity of the metal plate 15, this is provided with metallic fins 16 projecting therefrom. These fins 16 are angularly disposed with respect to the plate 15, and when the plate 15 is in position the fins 16 project toward the food compartment 2 of the refrigerator, thus materially increasing the heat conductivity of the metal insert plate 15. The metal insert plate 15 and projecting fins 16 are preferably of the same metal and may desirably be cast in one piece, or may be made of sections of plate 15 with corresponding fins 16 projecting therefrom that may be joined together to produce any size metallic insert plate desired.

The floor plate 3 with its metallic insert plate 15 is desirably positioned in the refrigerator to constitute the floor of the ice compartment, particularly when the floor plate and metallic insert plate are used to seal the ice compartment sub-

stantially against entry of air from the food compartment. Furthermore, the floor plate is desirably slanted slightly rearwardly in a front icer, as shown in Figure 2, so that as the ice melts there is a tendency for the ice to settle rearwardly in the box. This tendency is further enhanced by the added cooling effect obtained rearwardly in the refrigerator due to the increased cooling effects which are exhibited by the metallic plate 15 with depending fins 16. Consequently, referring to Figure 2, with the circulation of air in the direction shown in the arrows thereof, the warmer air in the food compartment 2 rises in the frontmost portion of the refrigerator, and moves against the bottom of the plate 8 of the floor plate 3. Some cooling effect is, of course, obtained at this point because the portion 8 of the floor plate 3 is in contact with the ice in the ice compartment 1. The air circulates in the direction of the arrows along the bottom of the portion 8 of the floor plate 3 into contact with the insert plate 15 and the depending fins 16, where it is given an increased refrigeration, and thereupon descends rearwardly of the box to go through this circulating cycle again.

By this construction, the cooling effect is carefully controlled and regulated, and a much more pronounced cooling effect may be maintained in this way by fins 16 carried by insert plate 15 constituting only a portion of the floor of the floor plate 3, particularly when the plate 15 and fins 16 are different from that constituting the metal of the portion 8 of the floor plate 3. When the entire floor plate is made of the same metal, usually aluminum alloy of relatively high heat conductivity, it has been found that sufficient control of the circulating air in the ice compartment is obtained, but due to the fact that the air rises from the food compartments and striking the plate of relatively high conductivity a more rapid melting of ice at the front of the ice compartment is developed, causing the ice to slope in the direction of the door, making it necessary, therefore, when refilling with ice to remove the ice in the ice compartment and turn same around in order that the top of ice slopes in the direction of the back of the ice compartment, therefore by having the floor portion of this ice rack of a metal of less conductivity than an aluminum alloy, less heat is transmitted to the air striking this fin as it rises from the food compartment, more heat being transmitted by the aluminum alloy back of the ice rack causing a more rapid melting of the ice at the back and therefore the ice will slope to the back.

The use of the two-part rack and plate as shown and described above is particularly important because it enables the opening 10 with the metallic insert plate 15 to be placed as desired within the ice compartment, either on the floor or the walls or otherwise, and the position may be varied as desired. Variation in position is found to be necessary, depending on whether the refrigerator is a so-called front icer or a rear icer or a side icer or a top icer. Under these circumstances, it is desired to control the point in the floor plate which gives the greatest cooling effect, and this is readily accomplished by means of the two-part floor plate 3, since the opening 10 can be placed at any portion of the floor plate that is desired, and the metallic insert plate used to control the particular point at which the greatest cooling effect will be obtained. The use of a wall plate similar to the floor plate 3 may be employed in those cases where the ice compartment has a side portion that is in contact with

the food compartment, although this is not necessary since the means set forth above have been found to exert sufficient control of the temperature with minimum consumption of ice.

5 The refrigerator may be supplied with the usual drain plate 17 and waste water outlet 18, the drain plate 17 being held in the refrigerator just below the metallic insert plate 15 and depending fins 16. In view of the condensate which 10 forms on the fins 16, the air in passing into contact with the metallic insert plate 15 and depending fins 16 receives a sufficient washing effect without having to pass into the ice compartment proper. Further, in view of the fact 15 that the metallic insert plate 15 rests on the ledges 11, 12 of the floor plate 3, there is usually sufficient passage between the metal insert plate 15 and the ledges 11 and 12 at some point over the floor plate to permit water which may 20 form in ice compartment 1 to pass between the metallic insert plate 15 and the ledges 11 or 12 into the drain plate 17.

When the floor plate 3 is not used to seal 25 the ice compartment, it may be provided with legs to rest on the usual bottom of the ice compartment of the refrigerator, as more particularly shown in my companion application, Serial No. 628,749, filed August 13, 1932, for Temperature regulator for refrigerators. And instead of 30 projecting fins 16 as hereinabove described, the elements projecting from the metallic insert plate 15 for increasing its heat conductivity may take any desired form, such as projecting pipes or lugs, as more particularly set forth in my companion 35 copending application, Serial No. 656,574, filed February 13, 1933, entitled "Refrigerators."

The floor plate 3 may be made in one piece, or may be made of an L-shaped member constituting the ledges 11 and 12 and the upstanding flanges 13 and 14 with a metallic plate portion 30 thereto.

In use, the two-part floor plate 3 is inserted 45 into the refrigerator to rest on supporting shoulders 4, 5, 6 and 7 and ice is then inserted in the ice compartment 1. The circulation of air within the food compartment into contact with the floor plate 3 brings the air first into contact with the plate portion 8 of the floor plate 3, where it is given an initial cooling effect, and then into contact with the higher heat conducting metallic insert plate 15 and depending fins 16 where the final cooling of the air is accomplished, after which the air then circulates through the food compartment, downwardly therein and 50 rearwardly thereof, and this circulation of air is, of course, repeated.

As pointed out above, due to the fact that the metallic insert plate 15 with depending fins 16 may be placed at any desired portion of the 55 floor plate 3, depending on the position at which the opening 10 is placed, and similarly because the opening 10 can be made of any size desired with a corresponding insert plate 15 to cover same, absolute control of the temperature is obtained with a minimum amount of consumption of ice. While the fins 16 or other projecting elements from the metallic insert plate 15 may be omitted, their use is preferred since an increased cooling effect is obtained by means thereof. 60 Similarly variation of the thickness of the metal in the plate portion 8 of the floor plate 3 and of the metal of the metallic insert plate 15 and depending fins 16 may also be utilized as a means of temperature control, since increased thickness 65 gives an increased cooling effect. The metallic

insert plate 15 with depending fins 16 may desirably be made of metal of high heat conductivity such as aluminum alloy or copper alloy, or any other desired metallic composition of high heat conductivity, while the remaining portion of the 5 floor plate 3, particularly the horizontal portion 8 thereof, is desirably made of a metal, such as sheet iron which may be galvanized, having a much lower degree of heat conductivity, so that the stated temperature control is more readily 10 effected.

While, of course, the floor plate 3 could be made a rigid immovable element constituting the floor of the ice compartment, it is desirably made removable, resting on the supporting ledges 15 4, 5, 6 and 7, so that the entire floor plate 3 and associated metallic insert plate 15 may be removed for sanitary reasons, and may be readily cleaned such as by washing and restored to 20 position.

Further as pointed out above in the preferred form of the present invention, the floor plate seals the ice compartment substantially against the entry of air from the food compartment. In such a structure where the entry of air from 25 the food compartment into the ice compartment is prevented, there is a minimum consumption of ice. Where the ice compartment is not sealed against the entry of air from the food compartment, lower temperatures can be obtained with 30 the same type of structure than in those cases where the ice compartment is sealed against the entry of air; but these lower temperatures thus obtained are obtained with a greater consumption of ice than that consumed when the ice 35 compartment is sealed against the entry of any substantial amount of air from the food compartment. And since in the latter instance with the sealed ice compartment, adequate temperature control and degree of temperature is 40 secured, it is unnecessary to permit circulation of air into the food compartment.

The invention described herein in any of its various forms may be employed in connection with refrigeration, either in the ice refrigerators 45 employed in the home, in refrigerator cars on railroads, in refrigerating trucks and automobiles used for transporting perishable articles, and in any other desired type of structure. In refrigerator cars or automobile trucks, there is 50 usually a bunker compartment containing the refrigerant. Such bunker compartment may then be provided with a side or floor plate of the character hereinabove described, and desirably such floor plate may actually constitute 55 the floor of the bunker compartment in the refrigerating structure in a manner now analogous to that described above in connection with the refrigerators specifically illustrating the present invention.

As pointed out, any type of refrigerant such as dry ice or water ice may be used, and these temperature regulators will serve their purposes adequately, regardless of the type of refrigerant employed, although they are particularly designed for use with water ice refrigeration. When dry ice is used in refrigerators, in the home type of refrigerator, thermostatic control of the temperature may be utilized in order to maintain the temperature in the food compartment at the 70 desired point.

The term "dry ice" is used herein to designate solid carbon dioxide, commonly referred to in the art as dry ice.

Having thus set forth my invention, I claim: 75

1. In combination, an ice refrigerator having ice and food compartments, a floor plate in said ice compartment, the floor plate being cut away to provide an opening therein, and a metallic plate supported by the floor plate closing the aforesaid opening therein, the metallic plate having a heat conductivity greater than that of the floor plate.
2. In combination, an ice refrigerator having ice and food compartments, a floor plate in said ice compartment, the floor plate being cut away to provide an opening therein, and a metallic plate supported by the floor plate closing the aforesaid opening therein, said metallic plate being provided with fins angularly disposed with respect thereto and extending toward the food compartment to increase the radiating surface of said metallic plate, the metallic plate having a heat conductivity greater than that of the floor plate.
3. A temperature regulator for refrigerators having the usual ice compartment, said regulator comprising a floor plate adapted to support ice in said ice compartment, the floor plate being cut away to provide an opening therein,
4. A temperature regulator for refrigerators having the usual ice compartment, said regulator comprising a floor plate adapted to support ice in said ice compartment, the floor plate being cut away to provide an opening therein, a metallic plate supported by the floor plate and closing the aforesaid opening therein, fins carried by said metallic plate and angularly disposed with respect thereto, the metallic plate having a heat conductivity greater than that of the floor plate.
5. A temperature regulator for refrigerators having the usual ice compartment, said regulator comprising a floor plate adapted to support ice in said ice compartment, the floor plate being cut away to provide an opening therein, a metallic second plate supported by the metallic floor plate and closing the aforesaid opening therein, the metallic second plate carrying fins angularly disposed with respect thereto.

JACOB H. HOFFBERGER. 25
